UNITED STATES PATENT OFFICE.

ABSAKOM BACKUS, JR., OF DETROIT, MICHIGAN.

LOCOMOTIVE-FURNACE.

SPECIFICATION forming part of Letters Patent No. 369,156, dated August 30, 1887.

Application filed June 11, 1887. Serial No. 240,990. (No model.)

To all whom it may concern:

Be it known that I, ABSALOM BACKUS, Jr., a citizen of the United States, residing at Detroit, in the county of Wayne and State of Michigan, have invented certain new and useful Improvements in Locomotive-Furnaces; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to the construction of the furnace of locomotive and marine boilers for generating steam and heating purposes.

The object of this invention is to provide a furnace that will fully, or nearly so, consume the gases, carbonic smoke, and volatile particles of combustion as a means of saving fuel, making a more rapid heating and steam-generating furnace, and to overcome the smoke nuisance.

The invention consists, mainly, in providing the ordinary fire-box with an arch of fire-brick, and in locating below said arch and the feed-door opening an angular or arched air-feeding grate or passage, whereby a sufficient supply of oxygen is admitted to the furnace below the arched wall, and in locating below the arch and within the fire-box a series of rocking clinker-breaking grates, with a dumping-grate at the forward end of the fire-box, all of which will be hereinafter fully set forth, and pointed out particularly in the claims.

In the accompanying drawings, forming a part of this specification, Figure 1 is a vertical central section of a locomotive-boiler and fire-box containing my invention. The grates and mechanism for operating them are in elevation. Fig. 2 is a horizontal section taken on the dotted line $\alpha\alpha$ of Fig. 1. Fig. 3 is a rear end elevation showing feed-door open. Fig. 4 is an isometrical of the ventilating or air-feeding grate.

As indicated in the drawings, B is the boiler; F, the flues; H, the fire box or chamber; A, the ash-pan; f, the dampers to the ash-pan; D, the floor of the cab, and D' the feed-door to the fire-box.

All of the foregoing parts are old, and therefore need no special mention.

B' B' are inclined bars located in the fire-box H—one on each side thereof. The forward ends are located at the bottom of the fire-box. 55 Their rear ends, rising, meet the inner rear end wall, K, of the fire-box slightly below the feed-door opening O, and are supported on the vertical rods r, having a foot or step, V, at the upper end, on which the bars lie, as shown in Fig. 1. In said side bars are journaled, as shown at 6, a series of rocking or clinker-breaking grates, 10. Each grate 10 has a depending arm, c, which is pivoted to the operating or angular rod m, having the vertical portion 2 and horizontal part 3, its rear end being pivoted at α to the vertical rod Z', which passes through the floor D of the cab, having a conical end, a, which is adapted to fill the head α' of the detachable operating-lever L, 70 which is shown in Fig. 1 as coupled to a like rod, Z. By placing the lever L onto the head α of the rod Z' and rocking back and forward, the clinker-grates 10 will be caused to tilt, as shown by dotted lines of Fig. 1. Said grates 75 may be of any suitable form. They are shown in Fig. 2 with interlocking fingers 4, (a form of grate in common use.)

Mounted on the supporting-bars B' B', at the rear of the series of rocking grates 10, is an angular ventilating-grate, N, which is L-shaped in cross-section, having a horizontal face, R, and vertical face R', each face being provided with a series of longitudinal openings or air-passages, e, as clearly shown in Fig. 4. 85

The ventilating-grate N crosses the fire-box at the rear end, its horizontal part R meeting the wall K of the fire-box just below the bottom of the feed-door opening O. (See Figs. 1 and 2.)

C is an arched wall having side walls, S, which are supported by the inclined bars B' B'. The side and arched walls are of a uniform length, and extend forward about half-way into the fire-box H, having the rear ends 95 abutting against the rear wall, K, of the fire-box. The under face of the arch C, at the feed-door opening O, is located slightly below the top of said opening, and is cut away or sloped, as shown at Y. (See Figs. 1 and 3.) The in-

cline Y of the arch causes the air passing through the ventilator or draft *n* in the feed-door D' to be deflected downward, thus conveying the products of combustion—such as air and gases—into the intense or incandescent heat under the forward end of the arch C, also affording sufficient room to properly admit the fuel through the feed-opening.

Between the front end of the fire-box and the series of grates 10 is a dumping-grate, J. Its ends are pivoted at 14 in the supporting-bars B' B', and has a depending arm, *h*, to the end of which is pivoted an operating-rod, *t*, having its rear end pivoted to the lower end 15 of the rod or bar Z', having the lever L mounted thereon, as shown in Fig. 1. By tilting said lever, as shown in Fig. 1, the dumping-grate J will swing down and backward, as shown by dotted lines in Fig. 1, thereby discharging any refuse thereon into the ash-pan A.

n' is a cross-bar mounted on the bars B' B', and projects slightly over the swinging edge of the grate J, whereby its upward movement 25 is arrested. The grate J is locked in position by swinging the button or angular dog *d* so as to engage with the upper end of the bar Z, as shown in Fig. 2, the dog being located on the floor of the cab; or any other suitable means 30 may be employed for locking the dumping-grate.

The furnace is to be operated as follows: The fuel is passed through the feed-door opening onto the clinker-bearing grates 10 below 35 the arch. No fuel or coal is to be placed on the ventilating-grate N, but forward thereof. The feed-door D' being then closed, the air passes freely upward from the ash-pan into the furnace below and at the rear end of the 40 arch through the openings *e* in the horizontal and vertical faces of the ventilating-grate N, as indicated by arrows in Fig. 1, thereby supplying the ignited products with a sufficient amount of oxygen to aid combustion. The 45 arch C is inclined, its forward end being the lower, whereby the flames are forced downward before escaping into the fire-box at the front end of the arch, thus preventing the escape of the gases and smoke.

50 In burning coal, as it becomes heated it congeals or melts and has a tendency to form one mass. To separate it, the operator places the

lever L on the upper end of the bar Z' and rocks the lever to and fro, tilting the clinker-bars 10, thereby loosening the mass to enable 55 the oxygen to mingle with the burning products to better aid combustion. The operator, before again charging the furnace, forces with a rod the burning products forward onto the grates 10 at the front of the fire-box and 60 places the fuel in at the rear end of the furnace, as before stated. The clinkers and refuse are forced forward onto the dumping-grate J, and are discharged therefrom into the ash-pan A by attaching the lever L to the upper end of the bar Z' and tilting it, as before 65 stated. Air may also be admitted into the fire-box through the register *n* in the feed-door.

Having thus fully set forth my invention, 70 what I claim as new, and desire to secure by Letters Patent, is—

1. In a furnace, and in combination, the fire-box, the inclined frame, the arched and side walls supported thereon, the series of 75 clinker-breaking grates, the dumping-grate, the ventilating-grate located in the rear end of the fire-box, and the feed-door opening through the fire-box below the arched wall, substantially as and for the purposes specified. 80

2. In combination with the fire-box, the arched wall, the feed-door opening in said fire-box below the arched wall, the inclined frame having journaled therein the series of grates 10, the ventilating-grate N, located at the rear 85 end of the fire-box and below the feed-door opening, and the mechanism for tilting the grates 10, substantially as specified.

3. In a furnace, the combination of the fire-box, the feed-door opening, the arched wall 90 located in the rear end of the fire-box over the feed-door opening, the series of grate-bars located below the arched wall, the ventilating-grate N, located below the feed-door opening 95 at an elevation to the series of grate-bars 10, and the dumping-grate located in the front end of the fire-box, as and for the purposes specified.

In testimony whereof I affix my signature in presence of two witnesses.
